VENDING MACHINE

Monte L. Levin, Roslyn Heights, N.Y., assignor to Continental Vending Machine Corp., Westbury, N.Y., a corporation of New York

Application December 2, 1957, Serial No. 48,729

Term of patent 14 years

(Cl. D52—3)

FIG. 1

Fig. 1 shows a front elevation of a vending machine, embodying my new design.

Fig. 2 shows a side elevation thereof.

The dominant features of the design reside in the portion shown in full lines.

What is claimed is:

The ornamental design for a vending machine, substantially as shown and described.
